Inventor:

Frank B. Byers

Patented Jan. 13, 1925.

UNITED STATES PATENT OFFICE.

FIRM B. BYERS, OF NEW YORK, N. Y.

CLASP OR FASTENING DEVICE.

Application filed March 19, 1920. Serial No. 367,102.

To all whom it may concern:

Be it known that I, FIRM B. BYERS, a citizen of the United States, residing at New York city, in the county of New York and State of New York, have invented certain new and useful Improvements in Clasps or Fastening Devices, of which the following is a specification.

This invention relates to devices for holding collars, or collars and neckties, etc. and is especially designed to clasp the ends of soft collars to prevent undue separation of the ends and hold them in a desirable position.

The primary object of the present invention is to provide a collar holder or fastener that will easily and firmly grip the ends or flaps of a collar, by merely inserting the collar in the gripping portion, and which device can be easily and cheaply formed from a single piece of metal or other suitable material.

A further object of the invention is to provide devices of this character in which the end portions of a bar or strip are divided into a series of tongues or arms, that are suitably deflected to have an engagement with the collar flaps, in which one of said tongues will cooperate with a pair of other tongues to grip the flaps.

In the accompanying drawing showing embodiments of my invention, Figure 1 shows in perspective one form of the device.

Fig. 2 is a side elevation of a modified construction.

Fig. 3 is a plan view of the latter.

Fig. 4 shows the device in use.

In the arrangement shown in Fig. 1, I provide a strip or a bar, having a central body portion 1, that is widened at the end portions 2 and 3. These end portions are provided with tongues 6 and 7, integral with the body at the inner end of each tongue, with the free end portion of each tongue preferably curved upward, as shown at 8 and 9. The end portions of the tongues are shown as curved downwardly, so that the tongues 6 and 7 and separate prongs 2', 2'', 3', 3'' or opposite portions of the end members have cooperating faces arranged to engage the opposite surfaces of the collar, as indicated in Fig. 4.

This device can be constructed in any suitable manner, being readily formed from sheet metal by dies, the tongues 8 and 9 be-

ing formed by slots 4 and 5, by a cutting die, and the parts bent as shown.

In the modification shown in Figs. 2 and 3, the central bar 12, is provided with tongues in slotted end portions, formed by slots or slits extending to the ends of the bar, whereby to produce three tongues, 16, 17, and 18 at one end, and three tongues 19, 14 and 15 at the other end portion.

By this means a series of connected tongues are formed at each end of the bar, that extend endwise from the central body portion 12. These tongues may be deflected at each end, as indicated in Fig. 2, in which the intermediate tongues 19, 18, are bent downwardly and then given a convex bend upwardly, as shown in Fig. 2. The two outer bars at each end are given a similar convex bend at their outer end portions, and these convex portions are positioned adjacent, so that at each end the outer pair of bars, that are substantially parallel, will engage one side of the collar flatwise while the intermediate tongue will engage the opposite side of the collar. The outer portions of these tongues will converge to form a loop or pocket 12, while the very extremities of the same diverge to facilitate the entrance of the collar therebetween.

My device thus has two parallel outer jaws comprising the lower body portions 14 and 15 and the tongue 19 struck up out of the same, both jaws being formed with opposite relatively out-turned ends, to form a clamping medium, and also two therebehind oppositely disposed concave recessed jaws constituting the pocket 12, to provide a longitudinal clasp, all of the jaws having flat-faced operating portions, whereby a thin piece of fabric, as the flap 10 of a collar, may be clasped between the outer parallel jaws and a thicker part of the fabric, as the hem of the said flap, simultaneously held by the inner oppositely disposed concave recessed jaws. These two pairs of jaws operate differentially and offer different degrees of resistance to the withdrawal therefrom of the said fabric in a lateral direction, and the whole of said operating portions are adapted throughout their entire extent to lie close to and to simultaneously evenly grasp both faces of different portions of the fabric of different thicknesses entered therein.

The entire structure is preferably given a curved or convex form, as shown in

Figs. 1 and 2. The device is applied to the end portions of the collar flaps 10, as indicated in Fig. 4 and will rest beneath the necktie 11, as shown. In each of the embodiments of my invention shown in Figure 1 and Figures 2 and 3 the clasp or fastener, which may obviously be used for a great variety of purposes in either single or dual form, is made from a single bar or piece of material which may, at one or both ends thereof, be slotted in an inward direction from the outer portion of the same. In Figure 1 the slit at the said outer portion of the device approaches near but is not extended to the end of the bar, while in Figure 3 the slit at the said outer portion of the device is cut through to the very edge of the said bar; wherefore the pairs of tongues will be separated at the outer portion of the bar both in the structure illustrated in Figure 1 and also in that shown in Figure 3.

By the said slits bifurcations or clamping jaws are formed as illustrated in Figures 1 and 3 which bifurcations recede from each other at the inner end of the slit and are then adapted to approach one another so as to lie adjacent to each other at the outer end of the slit to form automatic or self-acting clamping jaws and a relatively posterior cavity or recess.

In the duplex form of the invention shown in the drawings the fastening devices at the ends of the bar are also connected by a central part projecting from one of said fastening devices toward the other one.

It will thus be seen that according to the invention there is an edge-contact grip between the edge of the middle prong and the edge of each of the two opposite outside tongues, thus affording a dual longitudinal grip or resistance to the escape or withdrawal of the body of the collar from the clasp. There is also a face-contact grip between the face of the convex middle prong and the faces of the two opposite outside convex tongues that meet to form the outer boundary of the loops, wherefore in order to escape or to be withdrawn, the collar hem 50 has to bodily push the top prong upwardly and the two inner tongues downwardly, thus affording a dual transverse grip or resistance to the escape of the collar hem from the loop, the clasp thus providing a four-fold resilient contact grip.

In my device which is slotted in an inward direction from the outer portions thereof the spaced ends or single end tongues 2', 2'', 3', 3'', 14, 15, 16 and 17 comprising the dual end portions of my clasp in Figures 1 and 3 and the oppositely disposed flanges 6 and 7 and 18 and 19 form bifurcations which latter recede from each other at the inner end of the slit and then approach each other so as to lie adjacent to and opposite each other at

the outer end of the slit to form edgewise grip clamping jaws and a relatively posterior inclosed but continuously open centred loop, the bifurcations afterward receding from each other to form an entrance to the said loop which is normally closed at each end thereof, the said clamping jaws serving to provide an openable mouth of the inclosed open loop and to prevent accidental entrance into or withdrawal from the loop, the gripping properties of the abutting jaws thereby residing solely at the said mouth.

I claim:

1. A fastener of the class set forth comprising a bar having a central body slotted at the ends thereof to form two outer and intermediate end members each composed of a series of separate resilient tongues projecting endwise from the body, two of the tongues of each end member being positioned opposite a third intermediate tongue whereby collar end portions may be clamped between the intermediate tongue and the extremities of the other tongues at each end with an edge contact grip, the said tongues being relatively recessed to provide a clear space between the said tongues, each of the tongues having a convex portion exerting an opposed separate differential face contact grip near its end to hold the thickened edge of a collar therebetween, and terminating in oppositely disposed diverging extremities.

2. A fastener of the class described consisting of a bar forming a central body portion and slotted to provide jaws comprising two side and intermediate tongues on opposite ends of the body, each tongue being recessed at its inner part to provide separate interior abutments enclosing a pocket space and bent in opposite convex shape near the outer ends thereof to form a closure for the pocket, the ends of the intermediate tongues being free to enter the slits, whereby each jaw may exert an equal adjacent, but opposed and separate, differential edge contact grip on a soft collar entered between the intermediate and outer side tongues near the ends thereof to prevent accidental transverse withdrawal movement of the body of the collar from the tongues, the interior abutments also serving to resist by a face contact grip longitudinal passage thereby, and from the pocket, of the thickened edge of the collar, the said side and intermediate tongues terminating in oppositely disposed diverging extremities.

3. A fastener of the class described comprising a bar having a body portion and an end member composed of a series of separate resilient tongues projecting endwise from the body, two of the tongues of the end member being positioned opposite a third intermediate tongue whereby the end portions of an article may be clamped therebetween edgewise, said tongues being rela-

tively deflected to provide a clear space whereby the extreme end of the article may be held between the intermediate tongue and the extremities of the outer tongues face-
5 wise, the said tongues terminating in relatively oppositely disposed diverging extremities.

4. A fastener of the class described comprising a bar slotted to provide two side
10 tongues and an intermediate tongue, said tongues being relatively recessed at their inner parts to provide separate interior abutments enclosing a pocket and bent in

opposite convex shape near the outer ends thereof to provide a closure for the pocket,
15 the end of the intermediate tongues being free to enter the slit to enable the side and intermediate tongues to exert a differential edge contact grip on an article entered therebetween, the interior abutments serving to 20 exert a face contact grip on the portion of the article in the pocket, the said tongues terminating in relatively oppositely disposed diverging extremities.

In testimony whereof I affix my signature.
FIRM B. BYERS.
